(57) **CLAIM**

The ornamental designs for a tongue cleaner toothbrush, as shown and described.

DESCRIPTION

FIG. 1 is a perspective view of a tongue cleaner toothbrush showing the new design;

FIG. 2 is an enlarged perspective view of the design of FIG. 1, without handle;

FIG. 3 is an enlarged right side view of the design of FIG. 1; FIG. 4 is an enlarged top plan view of the design of FIG. 1; and,

FIG. 5 is an enlarged left side view of the design of FIG. 1. The broken lines illustrating a handle and/or a brushing means form no part of the claimed design.
